UNITED STATES PATENT OFFICE.

THEODORE L. VALERIUS AND OLAF LARSEN, OF FORT ATKINSON, WISCONSIN, ASSIGNEES TO THE CREAMERY PACKAGE MANUFACTURING COMPANY, OF CHICAGO, ILLINOIS, A CORPORATION OF ILLINOIS.

BOTTLE-CAPPING MECHANISM.

1,139,931.

Specification of Letters Patent. Patented May 18, 1915.

Application filed November 28, 1913. Serial No. 803,378.

To all whom it may concern:

Be it known that we, THEODORE L. VALERIUS and OLAF LARSEN, citizens of the United States, residing at Fort Atkinson, in the county of Jefferson and State of Wisconsin, have invented certain new and useful Improvements in Bottle-Capping Mechanisms, of which the following is a specification.

10 This invention relates to improvements in mechanisms for capping bottles such as are used to contain milk and cream.

One of the objects of the invention is to arrange the mechanism in such a way that 15 milk shall not be splashed upon the cap and the cap-feeding devices.

Another of the objects of this invention is to arrange the cap magazine in central position, *i. e.*, in line with the cap-seating plunger 20 and the centering bell, thereby making the mechanism easier to operate. Such central location of the magazine is rendered possible by placing the caps in the magazine with the printed side down, and providing 25 means for turning the caps through a half-revolution as they move into position to be applied to the bottle.

A further object of the invention is to provide means for effectively controlling the 30 cap during its passage from the magazine to the mouth of the bottle.

A further object is to provide a magazine that can be conveniently loaded with bottle 35 caps.

35 A further object is to embody the mechanism in a simple, convenient and reliable capping implement adapted to the purposes of milkmen and others who do not require large-capacity machines.

40 We have herein illustrated the invention as embodied in a hand-operated implement, without intending thereby to limit the invention to such use.

In the accompanying drawings, Figure 1 45 is an elevation of an implement embodying the features of our invention. Fig. 2 is a horizontal sectional view taken in the plane of dotted line 2 2 of Fig. 6. Fig. 3 is a top plan view of the implement. Fig. 4 is a sectional view taken in the plane of dotted line 4 4 of Fig. 3. Fig. 4^a illustrates a means for yieldingly holding the cap plunger in its elevated position. Fig. 5 is a perspective

view illustrating one method of filling the cap magazine with caps. Fig. 6 is a fragmental vertical sectional view illustrating the manner of operating the machine. Fig. 7 is a vertical sectional view illustrating the parts in a different position from that shown in Fig. 6. Fig. 8 is a horizontal sectional view taken in the plane of dotted line 8 of Fig. 7. Fig. 9 is a view on dotted line 9 of Fig. 6.

The embodiment herein shown of the invention comprises a tubular body portion 1 having an outwardly flaring guide flange or centering bell 2 at its lower end, the inner surface of said bell being made tapering or conical in order that when the implement is applied to the mouth of the bottle 70 the implement shall be automatically centered.

Alined with the body portion 1 is a cap magazine 4. Preferably, the cap magazine consists of a tube rigidly secured to the body portion 1 in any suitable manner as by means of the screw threads 5. (See Fig. 6.) A series of openings 6 may, if desired, be formed in the magazine 4 in order that the user may note whether the magazine 80 contains caps or not.

The column of caps in the magazine 4 rests upon a shelf 7 (Fig. 9). The distance between the top of the shelf 7 and the horizontal plane of the shoulder 8 (Fig. 6) is 85 substantially equal to the thickness of a single cap. A device to be later described pushes the bottom cap off from the shelf 7, and through an opening in the side of the body portion 1, the cap being discharged 90 onto a curved guide 9. 10 are vertical guard flanges which serve to guide the cap in its movement. The guide 9 is pivoted at its upper end to the body portion 1 at 11. Said guide extends through the space between 95 the flanges 10 and through an opening 12 in the side of the body portion 1, and is normally held with its lower end within the body portion by means of a coiled spring 13. Contact of the shoulders 14 on the guide 100 with the flanges 10 limits the movement of the guide under the influence of the spring 13. When pushed off the shelf 7, the advancing edge of the cap tilts downwardly by gravity, and on striking the guide 9, the 105 cap slides into the position indicated in Fig.

7, the cap having in its movement been inverted.

The caps are discharged from the magazine, one by one, by means of a slide 15 (Fig. 2) which is mounted for horizontal reciprocating movement in a guide 16, the slide being adapted to engage the edge of the lowermost cap and push it off the shelf 7.

For operating the implement there is provided a tubular handle or actuating sleeve 17 vertically movable upon the magazine 4. Rigidly attached to the handle 17 is a bracket 18 having a cam or inclined slot 19 therein. The slide 15 is provided with a roller 20 which lies within the slot 19. Said slot is of such formation that when the handle 17 is raised with reference to the body portion 1 and the magazine 4, the slide 15 will be projected inwardly to push the lowermost cap off the shelf 7 and onto the guide 9. The cap is forced into the seat provided for it in the mouth of the bottle by means of a plunger 21 vertically slidable within the body portion 1. A pin 22 extends withdrawably through the plunger 21. The projecting ends of the pin 22 fit freely within openings in the lower ends of two bars or links 23 which are rigidly connected at their upper ends to the handle 17. Cotter pins 22^a prevent displacement of the pin 22. The pin 22 extends through vertical slots 24 in the body portion, whereby the plunger 21, handle 17 and bracket 18 are held against axial displacement. The lower end of the bracket 18 is secured or braced by means of a stud 25 which is attached to the cap plunger 21 and extends through a slot 25^a in the body portion 1, said stud having an aperture through which a stud or lug 18^a on the lower end of the bracket 18 extends.

The parts of the implement are yieldingly held in the initial position by means of two spring fingers 26, Figs. 4^a, 6, 8 and 9. The fingers 26 are fixed at their lower ends to the body portion 1, and extend through the openings 26^a in said body portion into position to contact with the plunger 21 when the latter is in its upper position and lie below shoulders 21^a on said plunger. The fingers 26 yield to allow the plunger to descend when pressure is applied to the handle 17.

Milk-bottle caps are commonly put up for sale in pasteboard tubes. The present implement has been designed so that the magazine may be conveniently filled with caps directly from the tubes. When the magazine 4 is to be filled with caps from a tube, the implement is laid on its side on the table, the ends of the paper tube are cut away, that end of the tube which shows the printed side of the caps is telescoped over the magazine 4, and a suitable rod is inserted into the other end of the tube and the column of

caps pushed along until the foremost cap stops against the shelf 7. The implement may then be placed in upright position, and is ready for use. A collar 4^a on the magazine limits the descent of the pasteboard tube on the magazine.

If, in filling the magazine with caps, any of the caps should assume a position at an angle to the proper position, and the cap cannot be shaken out, the magazine 4 may be removed from the remainder of the implement and the misplaced cap removed from the magazine.

If loose caps (that is to say, caps which are not inclosed in tubes) are to be used with the implement, such caps may be sorted into a loading tube, such as shown at 28 in Fig. 5. The tube 28 may be telescoped with the magazine 4, and the caps pushed from the tube 28 into the magazine by means of a rod 85 or other suitable device.

If desired, a weight 29 may be placed in the magazine, above the column of caps, to assist in feeding the caps down in the magazine.

Assuming that the magazine 4 has been filled with caps arranged with the printed side down, and that the parts are in the position shown in Fig. 7, the mode of use is as follows: The operator places the implement 95 upon the mouth of a filled bottle and depresses the handle 17, thereby forcing the plunger 21 against the cap lying upon the guide 9. Said guide is thereby forced aside and the cap moves down through the body 100 portion 1 and onto the internal shoulder or seat in the mouth of the bottle. The operator then raises the handle 17. As soon as the plunger 21 reaches the shelf 7, the remainder of the implement rises with the handle 17, the implement being thus lifted off the bottle. In the upward movement of the handle 17, the slide 15 was moved inwardly to push the lowermost cap off the shelf 7 and onto the guide 9. The operator 110 may now apply the implement to the mouth of another bottle. It will be seen that bottles may be capped by simply applying the implement to a bottle, pushing the handle 17 downwardly, raising the implement, applying it to another bottle, and so on. There are no levers for the user to operate, but, on the contrary, the device is arranged to be actuated with one hand and by simple pressure.

The pressure is applied axially of the 120 bottle, as the handle is aligned with the cap-seating plunger and the centering bell. 115

It will be observed that the cap is delivered on the upstroke of the plunger, after the bottle has been capped; therefore, the 125 upper side of the cap and the cap-forwarding mechanism cannot be splashed with milk. Such splashing has been an objectionable feature of prior implements, as the milk caused the cap-forwarding mechanism 130

to become gummed up. The caps being guided from the magazine to a point below the cap-seating plunger 21 by the spring-held guide 9, there is no possibility of the implement being clogged by reason of an improperly positioned cap.

We claim as our invention:

1. A bottle-capping mechanism comprising a centering bell, a body portion, and a cap magazine, all of said parts being axially aligned, cap-feeding means including a guide extending laterally outside said body portion, cap-seating means, and means for actuating said feeding and seating means.
2. A bottle-capping mechanism comprising a body portion and a cap magazine axially aligned, a cap-feeding device, a vertically movable cap-seating plunger within said body portion, and means for actuating the cap-feeding device on the upstroke of the plunger.
3. A bottle-capping mechanism comprising a portion adapted to be applied to the mouth of a bottle, a cap-magazine, a cap-feeding device all of said parts being axially aligned, and a yieldingly mounted guide for directing the cap discharged by the cap-feeding device to proper position above the mouth of the bottle.
4. A bottle-capping implement comprising a tubular body portion adapted to be applied to the mouth of a bottle, a tubular cap magazine alined with said body portion, a cap-feeding device, a cap-seating plunger in the body portion, an actuating handle connected to the plunger, and an operative connection between the handle and the cap-feeding device.
5. A bottle-capping mechanism comprising a body portion adapted to be applied to the mouth of a bottle, a cap magazine attached to said body portion in vertical alinement therewith, a cap-feeding device, a cap-seating plunger reciprocable vertically in said body portion, and a single device for actuating said cap-feeding device and said cap-seating plunger.
6. A bottle-capping implement comprising a body portion, a cap magazine attached to said body portion in vertical alinement therewith, a cap-seating plunger in said body portion, cap-feeding means, and hand-hold means reciprocable vertically for actuating the cap-feeding means and the cap-seating plunger.
7. A bottle-capping implement comprising a body portion, a cap magazine attached to said body portion and axially alined therewith, a cap-seating plunger reciprocable vertically in said body portion, cap-feeding means, hand-hold means reciprocable vertically for actuating the cap-feeding means and the cap-seating plunger, and means for yieldingly locking the actuating member in its upper position.

8. A bottle-capping implement comprising a body portion adapted to be applied to the mouth of a bottle, a cap magazine attached to said body portion, a cap-feeding device, a cap-seating plunger reciprocable within said body portion, a sleeve adapted to be grasped in the hand of the operator, said sleeve surrounding the magazine and being reciprocable longitudinally thereof, and actuating connections between said sleeve and said cap-feeding device and said cap-seating plunger.

9. A bottle-capping mechanism comprising a tubular body portion adapted to be applied at one end to the mouth of a bottle, a tubular cap magazine attached to the other end of the body portion, a cap-feeding device, a cap-seating plunger reciprocable within said body portion, a member reciprocable longitudinally of said cap magazine, and actuating connections between said member and said cap-feeding device and said cap-seating plunger.

10. A bottle-capping mechanism comprising a body portion adapted to be applied to the mouth of a bottle, a cap magazine attached to said body portion, a cap-supporting shelf below said cap magazine, a cap-feeding slide reciprocable transversely of the cap magazine and above said shelf, means arranged to receive caps from the cap-feeding slide and guide them into proper position in the body portion, a cap-seating plunger, an actuating device reciprocable longitudinally of the mechanism, a member rigidly attached to said actuating device, the second mentioned member having a cam-slot therein, a device attached to said slide, extending into said cam-slot, and a connection between said actuating device and said cap-seating plunger.

11. In a bottle-capping mechanism, a body portion, a cap magazine alined therewith, a device for feeding caps from said magazine, a pivoted guide arranged to guide caps into proper position in the body portion, a cap-seating plunger, said guide being arranged to yield laterally to allow the plunger and the cap to pass, and means for actuating said cap-feeding device and said plunger.

12. In a bottle-capping mechanism, a body portion having an open side, a cap magazine attached to said body portion, a device for feeding the caps from said magazine, a curved guide attached at its upper end to said body portion, the lower portion of said guide extending through the open side of the body into the interior of the body portion, said guide being arranged to guide the caps discharged from the magazine into proper position in the body portion, a spring tending to hold the guide in the body portion, a cap-seating plunger, said guide being arranged to yield laterally to allow the cap

and the plunger to descend, and means for actuating said cap-feeding device and said plunger.

13. In a bottle-capping mechanism, a tubular body portion, a conical centering flange at the lower end of said body portion, a tubular cap magazine alined with the body portion and attached to the upper end of said body portion, a curved guide attached 10 at its upper end to said body portion, the lower end of said guide extending through the open side of the body portion, a cap-supporting shelf in the body portion at the lower end of the magazine, a cap-feeding 15 slide reciprocable horizontally above said

shelf, a cap-seating plunger reciprocable vertically in said body portion, a lateral projection on the plunger extending through a vertical slot in said body portion, a sleeve surrounding the cap magazine, a connection between said sleeve and said projection, and an actuating connection between said slide and said first mentioned connection. 20

In testimony whereof we affix our signatures in presence of two witnesses.
